UNITED STATES PATENT OFFICE

110,334

DESIGN FOR A QUOIT OR SIMILAR ARTICLE

William Anthony, Hanover, Pa.

Application November 17, 1937, Serial No. 72,953

Term of patent 14 years

To all whom it may concern:

Be it known that I, William Anthony, a citizen of the United States of America, residing at Hanover, in the county of York and State of Pennsylvania, have invented a new, original, and ornamental Design for a Quoit or Similar Article, of which the following is a specification, reference being had to the accompanying drawing, forming part thereof, wherein

Fig. 2 is a side elevation thereof.

I claim:

The ornamental design for a quoit or similar article, as shown.

WILLIAM ANTHONY,
